[57] CLAIM

The ornamental design for a combined needle disposal container and glove dispenser, as shown and described.

DESCRIPTION

FIG. 1 is a front elevational view of a combined needle disposal container and glove dispenser showing our new design;

FIG. 2 is a top plan view thereof;

FIG. 3 is a left side elevational view thereof, the right side being a mirror image of that shown, except for the absence of the hinge elements;

FIG. 4 is a bottom plan view thereof;

FIG. 5 is a perspective view thereof; and

FIG. 6 is a right side elevational view of an alternate embodiment thereof, the only difference residing the absence of the grillwork on the side panel.

7 1 9.5.
